THREE WHEEL MOTORCYCLE

George K. Laverty, 200 N. 8th St.,
Carlisle, Iowa 50047

Filed Sept. 24, 1969, Ser. No. 19,290

Term of patent 14 years

Int. Cl. D12—11

U.S. Cl. D90—8

FIG. 1 is a top plan view of the three wheel motorcycle showing my new design;

FIG. 2 is a side elevational view as seen from the right side of the device in FIG. 1, the opposite side being substantially a mirror image thereof;

FIG. 3 is a front end view; and

FIG. 4 is a rear end view.

I claim:

The ornamental design of a three wheel motorcycle, substantially as shown and described.
